A. FYRBERG.

FIREARM.

APPLICATION FILED APR. 22, 1907.

UNITED STATES PATENT OFFICE.

ANDREW FYRBERG, OF HOPKINTON, MASSACHUSETTS.

FIREARM.

No. 887,784.

Specification of Letters Patent. Patented May 19, 1908.

Application filed April 22, 1907. Serial No. 369,518.

To all whom it may concern:

Be it known that I, ANDREW FYRBERG, a citizen of the United States, residing at Hopkinton, in the county of Middlesex and State of Massachusetts, have invented a new and useful Firearm, of which the following is a specification.

This invention relates to fire arms, the principal objects thereof being to provide an improved safety for effectively preventing the firing pin from being actuated to fire the arm whenever the hammer is accidentally allowed to swing down from any position except that at which it is fully cocked or ready for repeated firing, so that it will be impossible to discharge the fire-arm accidentally; to locate the safety in such position that it will act directly on the hammer and not through a train of mechanism; to provide for operating the safety and firing pin after firing, in such a manner as to retract the hammer when the firing pin is retracted; to provide an improved means for controlling the safety, preferably in the form of a swinging turret having projections for engaging the trigger, the safety, and an operating spring for the turret; and to combine the same with an improved form of cylinder lock operated by the trigger.

Further objects and advantages of the invention will appear hereinafter.

Reference is to be had to the accompanying drawings which illustrate a preferred embodiment of the invention as applied to a certain type of revolver, and in which

Figure 1 is a side elevation of such a revolver, with the parts in section and portions of the frame removed to show interior construction, the hammer being shown in the position which it assumes when the safety operates to prevent the firing of the arm. Fig. 2 is a similar view of a portion of the mechanism showing the parts in the position which they assume when the hammer is cocked. Fig. 3 is a similar view showing the position assumed when the gun is fired. Fig. 4 is another view of a similar character showing the parts in the position assumed when the hammer is drawn back by the trigger for repeated firing. Fig. 5 is an end elevation of certain elements of the device. Fig. 6 is a side elevation of the turret or swinging element for operating the safety and trigger, and Fig. 7 is a plan of the same.

It is to be understood that while the invention is illustrated as applied to a revolver,

it is capable of application in general to many styles of fire-arms.

The main features of the invention will be described first with special reference to Fig. 60 1. This figure illustrates a revolver frame 10 of ordinary construction having a side swinging cylinder 11 provided with a ratchet 12 which may operate as a cartridge ejector when the cylinder is swung outwardly. The 65 construction of the ejector mechanism is not illustrated, as it does not constitute a part of this invention. The frame 10 is provided with a trigger guard 13 of any ordinary construction, and a trigger 14 is mounted in the 70 usual position. On this trigger is a projection 15 which is provided with a pin 16. On this pin is pivoted a pawl 17 having a projection 18. On the pin is wound a coiled spring 19 engaging a fixed portion of the arm 75 15 at one end, and having an end engaging the projection 18 on the pawl 16 for normally forcing this pawl into position to engage the ratchet as the trigger is pulled to turn the cylinder. The pawl has a notch 20 which is 80 engaged by the edge of the arm 15 to positively insure the correct amount of motion for the pawl. The end of the projection 15 is adapted to engage a fixed projection 21 on the hammer 22. The hammer is pivoted on 85 a stationary stud 23 to swing in the usual manner. When the trigger is pulled back from the position indicated in Fig. 1, the end of the projection 15 moves upwardly and engages a pivoted arm 24 on the hammer which 90 is held in normal position by a spring 25 in a well known manner. The projection 15 operating on this arm serves to pull the hammer back to firing position in a well known manner, and when it passes beyond this 95 arm the hammer is free to swing inwardly to fire the arm being propelled by the firing spring 26.

The frame 10 is provided with a hub 30 concentric with the stud 23 on which is 100 pivotally mounted a swinging frame or turret 31 designed to control the operation of the safety. This turret is provided with three projections 32, 33 and 34 each mounted on an arm preferably integral with the turret 105 and extending at an angle to the plane thereof. The projection 34 is engaged by a strong spring 35 which tends to swing the turret counter-clock-wise for a purpose which will be described hereinafter. This spring is 110 shown like the spring 26 as located in the hollow handle of the frame but it may be in

any desired position and of any convenient form.

The projection 32 is located in such position as to engage a curved surface 36 on the trigger which constitutes a cam for positively swinging the turret when the trigger is pulled.

It will be seen that the pulling of the trigger moves the projection 32 upwardly and swings the turret in opposition to the spring 35.

10 When the turret is in the position shown in Fig. 1, the trigger being forward, the outer surface of the projection 33, which is substantially perpendicular to a line drawn from it to the center of the turret, engages a projection 37 on a safety 38 and holds it in safe position.

On account of the above mentioned direction of the surface of the projection 33 it will be seen that the safety is held positively in 20 safe position, although the turret is held in this position by a spring. Any force brought to bear on the safety to swing it into firing position will act directly on the flat surface of the projection 33 and will have no tendency to swing it about its pivot, as the parts are practically on a dead center. Now, if the hammer is drawn back to a position short of firing position and allowed to snap down again, the first operation of drawing the 30 hammer back may release the safety, but the instant the hammer is allowed to snap back, the safety will be positively held in safe position again so that a notch 39 in the hammer will engage it, as indicated in Fig. 1. The 35 reason for this is as follows: If the trigger is pulled or if the hammer is drawn back to any position short of that at which the projection 15 on the trigger passes over the end of the pivoted arm 24 this arm will be in engagement with the projection on the trigger or at least will come into engagement with it before the hammer can reach firing position and consequently, any motion of the hammer will be transmitted back to the trigger 40 so as to permit the same to be retracted with the hammer and allow the turret to yield to the action of the spring 35 so as to bring the projection 33 into proper position. Thus, it will be seen that although the safety tends 45 to force the hammer back immediately after firing more rapidly than the trigger would be retracted, this will not prevent the safety from being brought back to safe position.

When, however, the hammer is cocked by 50 bringing the trigger back to cocking position, (Fig. 2) the swinging of the trigger to this position moves the turret into such position as to free the safety and allow the firing spring 26 to act and the arm to be fired, the 55 tension of the spring 35 being overcome by the pull on the trigger. When it is desired to fire repeatedly also, the swinging of the trigger into position to free the end of the arm 24 will also operate to free the safety and 60 permit repeated firing, but if the trigger is

released at any intermediate point, the safety will be forced into safe position as has been described. After the arm is fired the trigger springs forward and causes the safety to be retracted to withdraw the firing pin and 70 hammer.

It will be observed that on the safety is mounted the firing-pin 40. This forms an exceedingly convenient and simple arrangement, whereby the firing pin is integrally 75 mounted on the safety itself, and is always controlled by the safety to keep it in proper position for necessary operation.

When this invention is used in connection with a revolver or any other fire-arm having a rotating cylinder, it is preferably used in combination with a lock for the cylinder, which in the present instance is constructed as follows: A pivoted member 41 is pivoted on a stud 42 in such a manner that a tongue 43 thereon can project through the pivoted member into position to engage a recess 44 in the cylinder and lock the same in position. This pivoted member has a tongue 45 thereon which in the position shown in Fig. 1, 90 engages a spring-pressed pin 46 located in a recess in the trigger. Now when the trigger is pulled, this pin positively engages the tongue 45 and swings the pivoted member on its pivot to positively retract the locking tongue 43, but before the trigger is pulled back very far, the spring-pressed pin passes over the tongue 45 and permits the spring 47 which controls the pivoted member to force the lock back into position to engage the 95 next notch on the cylinder. It will be understood that while the trigger is being pulled the pawl 17 operates to turn the cylinder one step. Now when the trigger again moves back, the slanting upper face of the pin 46 engages the curved lower face of the tongue 45 and readily passes the same without disturbing its position, so that it returns to the position shown in Fig. 1 ready to unlock the cylinder.

It will be seen that a fire-arm provided with this invention in the form shown, or any other form coming within the scope of the claims is absolutely safe, as after the trigger is pulled from its normal position any release of the trigger will only result in bringing the safety back and allowing the hammer to engage it without firing the arm, and that firing from cocked position and repeated firing are not interfered with, while an efficient form of cylinder lock is combined with the trigger. These results are accomplished largely by the improved construction and location of the safety, and by the employment of the turret together with other combinations and arrangements as have been described, and as will be pointed out in the claims.

While I have illustrated and described the invention as embodied in a particular form and applied to one kind of fire-arm, I am 130

aware that many changes may be made therein by any person skilled in the art, and that it may be applied to substantially all kinds of fire-arms without departing from the 5 scope of the invention as expressed in the claims. Therefore, I do not wish to be limited to the particular features of construction or type of fire-arm shown in the drawings, but

10. What I do claim is:—

1. A fire arm having a hammer, a safety therefor mounted to swing on a stationary pivot and provided with a firing pin, and means for positively preventing the safety 15 from swinging and for holding it in position to engage the hammer to check its motion before the stroke of the hammer is completed.

2. In a fire arm, the combination with a hammer, of a pivoted safety therefor having 20 a firing pin thereon and a projection, said firing pin and projection being on opposite sides of the pivot, a swinging turret provided with a projection for engaging said projection on the safety so as to move the safety to safe 25 position and positively to hold it in safe position, and a trigger for controlling the operation of the turret.

3. In a fire arm, the combination of a hammer a pivoted safety therefor having a 30 projection thereon at one side of the pivot, a turret having means for moving the safety and positively holding it in safe position, and a spring for operating the turret.

4. In a fire arm, the combination with a 35 pivoted hammer having a notch therein, of an independently pivoted safety adapted to engage in said notch and hold the hammer back from firing position, said safety having a firing pin thereon, and a projection on the 40 opposite side of the pivot from the firing pin, and a movable member for engaging said projection to operate the safety adapted to move into engagement with the end of said projection to hold it positively in safe position.

45. As an article of manufacture, a turret for operating the safety of a fire-arm comprising a circular portion adapted to swing on a pivot and having three projections, one 50 for engaging the safety, one for engaging the trigger, and the other by which the turret may be operated.

5. In a fire-arm, the combination of a swinging turret having three projections 55 thereon, an operating spring for constant engagement with one of said projections, a trigger for engaging and controlling another of the projections, and a safety adapted to be moved to safe position by the third projection.

60. In a fire-arm, the combination of a swinging turret having three integral projections thereon, a swinging safety adapted to be engaged by one projection, a spring 65 adapted to engage another projection in

position to bring the safety to safe position, and a trigger having a curved surface engaging the third projection for overcoming the spring and releasing the safety from safe 70 position when the trigger is pulled to firing position.

8. In a fire-arm, the combination of a safety, a turret having an arm engaging the safety to operate it and to positively lock it in safe position, a spring for operating the 75 turret and normally holding the turret in such position as to bring the safety to safe position, and a trigger having means for operating the turret to bring the same to such position as to release the safety when 80 the trigger is moved to firing position, said spring acting to hold the safety in safe position in all other positions of the trigger.

9. In a fire-arm, the combination of a safety, a turret having an arm for engaging 85 and operating the safety and lock it in safe position, a spring for normally operating the turret to such position as to bring the safety to safe position, and a trigger having a surface adapted to engage the turret to move 90 the same to such position as to release the safety when the trigger is moved to firing position and to allow the turret to be moved by the spring to safe position when the trigger is in any other position than that for 95 cocking the fire-arm or repeating.

10. In a fire-arm, the combination with a hammer of a safety, a turret for operating the safety, a spring for normally moving the turret so as to bring the safety to safe 100 position, and a trigger having means for operating the turret to release the safety when the trigger is in firing position, and to move the safety to retract the hammer from firing position when the trigger is released.

11. In a fire-arm, the combination of a hammer, a trigger, a safety pivoted independently of said trigger and means connected with the trigger for releasing the 110 safety from safe position when the trigger is in firing position, and for setting the safety into position to retract the hammer when the trigger is released.

12. In a fire-arm, the combination of a 115 swinging safety, means for holding the safety positively in safe position and resilient means for operating the holding means.

13. In a fire-arm, the combination of a safety, a swinging turret having a surface 120 adapted to positively hold the safety in safe position on a dead center, and a spring for yieldingly forcing the turret into position to hold the safety on a dead center.

14. In a fire arm having a cylinder, the 125 combination of a trigger, a stud mounted thereon, a pawl pivoted on said stud and having means for turning the cylinder, and a spring coiled on said stud bearing on the surface of the trigger and engaging the pawl 130

for normally holding the pawl in operative position.

15. In a fire-arm, the combination of a rotary cylinder, a trigger, a stud on which 5 said trigger is pivoted, a lock for the cylinder pivoted at a point in front of the trigger, a spring in front of the trigger for normally forcing the lock into locked position, said lock having a tongue projecting toward the 10 trigger and located in front of the same, and a locking tongue for engaging the cylinder extending over the top of the trigger and over said stud, said tongue having a recess for receiving said stud, a spring-pressed pin 15 mounted on the front side of the trigger for

engaging said first mentioned tongue, said pin and tongue having inclined contacting surfaces whereby when the trigger is permitted to swing back to normal position the pin will pass over the tongue and be left in 20 position to engage the same to unlock the cylinder on the next motion of the trigger.

In testimony whereof I have hereunto set my hand, in the presence of two subscribing witnesses.

ANDREW FYRBERG.
